[57] CLAIM

The ornamental design for a boat, as shown and described.

DESCRIPTION

FIG. 1 is a top view of the boat;
FIG. 2 is an elevation side view of the right side of the boat,
the opposite side being the same. The boat is illustrated in an
attitude in which the boat rests in water;
FIG. 3 is a bottom view of the boat;
FIG. 4 is a front view of the boat; and,
FIG. 5 is an end view.
